UNITED STATES PATENT OFFICE

165,812

SWIMMING TRUNKS

Alfred O. Wupperman, Fort Worth, Tex.

Application January 15, 1951, Serial No. 13,803

Term of patent 14 years

(Cl. D3—17)

To all whom it may concern:

Be it known that I, Alfred O. Wupperman, a citizen of the United States of America, residing at Fort Worth, in the county of Tarrant, and State of Texas, have invented a new, original, and ornamental Design for Swimming Trunks, of which the following is a specification, reference being had to the accompanying drawing, forming part thereof.

Fig. 2 is a rear perspective view thereof.

Fig. 3 is a side elevational view.

I claim:

The ornamental design for swimming trunks, as shown.

ALFRED O. WUPPERMAN.
